(No Model.)

P. M. SHARPLES,
CENTRIFUGAL LIQUID SEPARATOR.

No. 402,624.

Patented May 7, 1889.

ATTORNEY

UNITED STATES PATENT OFFICE.

PHILIP M. SHARPLES, OF WEST CHESTER, PENNSYLVANIA.

CENTRIFUGAL LIQUID-SEPARATOR.

SPECIFICATION forming part of Letters Patent No. 402,624, dated May 7, 1889.

Application filed February 29, 1888. Serial No. 265,671. (No model.)

To all whom it may concern:

Be it known that I, PHILIP M. SHARPLES, a citizen of the United States, residing at West Chester, in the county of Chester and State of Pennsylvania, have invented certain new and useful Improvements in Centrifugal Liquid-Separators; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to a centrifugal machine adapted to separate compound fluids—such as milk—and to continuously deliver their constituent parts.

The object of my improvements is to provide a novel means of delivery which is not only economical, but which also prevents the possibility of clogging the outlet, and allows the width of the stream to vary with the amount of the discharge.

Figure 1 shows in sectional elevation one form of centrifugal vessel provided with my outlet. Fig. 2 is a plan of the same. Fig. 3 shows a vessel without a projecting neck such as is shown in Fig. 1, but having the same form of outlet. Fig. 4 is a plan of a vessel having an eccentric opening or mouth which forms an equivalent outlet.

A represents a separating-vessel attached to a rotatable axis, B, which is guided in a bearing attached to the inclosing-case C.

A' is a projecting neck terminating with an internal flange which somewhat contracts the opening or mouth A⁴.

A³ is a depression or notch in this flange which extends the otherwise circular opening.

D and D' are annular receiving-vessels supported on the fixed casing C.

E is a fixed inlet-nozzle through which the milk is admitted to the separating-vessel.

The means of supporting and revolving the shaft B are not shown.

The vessel shown in Fig. 3 has an opening or mouth with similar depression for outlet, but is formed without the neck, which is not an essential element of my arrangement.

Fig. 4 shows an opening which is perfectly circular, but which is not concentric with the axis on which the vessel rotates. Different points of said opening are therefore at varying distances from the center of rotation, and the same object is thus attained as by means of the depression or notch A³.

I am aware that centrifugal separating-vessels have been constructed in which a fluid was discharged over the level edge of the vessel, also through holes in a projecting neck below the edge; and Patent No. 293,314 shows a delivery-notch in the upper edge of a vessel having such a projecting neck. The notch in the upper edge above referred to, and also the discharge-holes below the edge, require more or less of a projecting neck. The fluid is discharged as soon as it reaches the height of the hole or notch, and does not flow over the edge of the vessel. When the fluid is discharged over the upper edge, it is apt to overflow equally at all points. With my arrangement the upper edge may be perfectly level, yet the liquid may be made to flow over it in any desired width of stream. The centrifugal force throws the fluid as far as possible away from the center of rotation, and the continuous supply of new fluid causes the lighter constituent to rise over the edge of the vessel at the part of the nozzle which is farthest from that center, while it is otherwise confined by the nearer part of the top or flange.

Having thus fully explained my invention, what I desire to secure are the following claims:

1. A centrifugal separating-vessel provided with a top opening or mouth eccentric with the axis of said vessel, substantially as and for the purpose set forth.

2. A centrifugal separating-vessel provided with a top opening or mouth mainly concentric with the axis of said vessel, but having a depression or notch, A³, substantially as and for the purpose set forth.

In testimony whereof I affix my signature in presence of two witnesses.

PHILIP M. SHARPLES.

Witnesses:

Jos. T. PRICE,

LOUIS HARTMANN.
